UNITED STATES PATENT OFFICE

109,023

DESIGN FOR A TIMING CASE

Raymond E. Patten, Wilton, Conn., Frederick W. Hottenroth, Jr., Lynn, Mass., and Harry R. Crago, Verona, N. J., assignors to General Electric Company, a corporation of New York

Application February 9, 1938, Serial No. 75,020

Term of patent 14 years

To all whom it may concern:

Be it known that we, Raymond E. Patten, Frederick W. Hottenroth, Jr., and Harry R. Crago, citizens of the United States; Patten residing at Wilton, in the county of Fairfield, State of Connecticut; Hottenroth residing at Lynn, in the county of Essex, State of Massachusetts; and Crago residing at Verona, in the county of Essex, State of New Jersey, have invented a new, original, and ornamental Design for a Timing Case, of which the following is a specification,

reference being had to the accompanying drawing, forming a part thereof.

The figure is a front perspective view of a timing case showing our new design.

We claim:

The ornamental design for a timing case as shown.

RAYMOND E. PATTEN.
FREDERICK W. HOTTENROTH, JR.
HARRY R. CRAGO.
